UNITED STATES PATENT OFFICE

ERNEST S. WOOLLEY, OF CHICAGO, ILLINOIS

NECKTIE HOLDER

Application filed February 12, 1930. Serial No. 427,666.

This invention relates to a novel and improved necktie holder.

The main object of this invention is to provide a simple and inexpensive device which 5 can be readily and removably attached to a collar for holding a necktie in the proper elevated position thereon. Another object of this invention is to provide necktie retaining means which contains resilient clasping means thereon, whereby it can be readily clasped in its operative position on a collar and can also be readily detached therefrom.

These and other objects and advantages are attained with this invention, as will become 15 apparent from the following description, taken in connection with the accompanying drawing, in which

Fig. 1 is an elevational view showing my improved holder mounted in position on a 20 collar for holding the necktie in its proper elevated position thereon.

Fig. 2 is an elevational view of the necktie holder.

Fig. 3 is a top plan view thereof.

Fig. 4 is a vertical sectional view, taken 25 on line 4—4 of Fig. 1.

Fig. 5 is an enlarged vertical sectional view, taken on line 5—5 of Fig. 2.

Fig. 6 is a top plan view showing the holder 30 provided with a pin or peg to engage into the necktie.

In the drawing my invention is illustrated in connection with a well known type of turn-down collar which includes a band 10 having 35 its ends 11 and 12 overlapped and held together by a collar button 13, and from which band depends the down-turned outer part or flap 14 of the collar. A necktie 15, of the four-in-hand type, is shown in position underneath the adjacent ends of flap 14, forward of the band ends 11 and 12; and the band or strap 16 of the necktie extends around collar band 10, beneath flap 14.

This improved and inexpensive necktie 40 holder is provided for retaining the necktie

15 in a proper elevated position on the collar, and prevent it from sagging to an unsightly position thereon.

The drawing illustrates my necktie holder in its preferred form of construction, which 50 comprises a main member or bar 20, the same being curved and being mounted to extend in a direction circumferential of the collar band, and so as to have its front and intermediate portion bear against the rear face of the upper part or looped part 15' of the necktie. Near each of its two ends this bar is bent rearwards to provide an offset portion or shoulder 21, and to place the main intermediate portion of the bar forwardly so as 55 to more effectively bear and press against the necktie and hold it firmly in its desired elevated position on the collar. Each end part is then bent downwards from said off-set portion thereby forming a depending finger 22, 60 and the outer end portion is then curved and bent upwardly from said depending finger thereby forming an upstanding finger 23, 65 said fingers providing looped means or clasping means at each end of the bar and integral 70 therewith, for clasping therein the band part 10 of the collar and enabling this holder to be readily slid upwardly into position on the collar and to retain a firm grasp thereon. The bar and its clasping means are made of 75 resilient material, so that the same can be readily mounted in position on the collar and can also be readily removed therefrom and at the same time will grasp it firmly to remain securely thereon.

In Fig. 6 of the drawing I have shown this holder furthermore provided with a pin or peg 24, which is preferably arranged to project forwardly from the central part of the bar 20', to engage or pierce into the rear portion of the upper looped part 15' of the necktie and thereby more positively preventing any sagging or downward sliding of the necktie on the holder and on the collar.

This invention thus provides a holder which is readily mounted on the collar and will hold the necktie in a proper elevated position thereon, and can also be readily removed; and this holder is so arranged that its main part of the bar is concealed behind the necktie, while the bar is of sufficient length to have the clasping means at its ends concealed underneath the down-turned flap portion of the collar, so as to entirely hide this holder in its operative position; and it can also be produced at a very low cost. It should also be noted that this holder does not mar or spoil either the collar or the necktie; but smoothly 10 slides into and out of position on the collar.

What I claim as my invention and desire to secure by Letters Patent is:

1. A necktie holder comprising means to bear against the necktie and hold it in an elevated position on a collar, and resilient looped finger means on said means for clasping the collar band and to enable convenient and quick mounting of said holder on the collar and removal therefrom.

2. A necktie holder for holding a necktie in an elevated position on a turn-down collar, said holder comprising a member to bear against the rear of the necktie and retain it in an elevated position, and means on said member for readily and removably mounting it on the collar band, said holder being entirely concealed by said necktie and collar.

3. A necktie holder for holding a necktie in an elevated position on a turn-down collar, said holder comprising a curved bar to extend in a direction circumferentially of the collar, a rearwardly extending offset portion at each end of said bar, and looped clasping means of resilient material including a finger depending from said offset portion and a finger curved upwards from said depending finger, for clasping the band of the collar between said fingers and to provide for ready mounting of the holder on the collar and for ready removal therefrom, said bar bearing against the rear upper part of the necktie to retain the same in an elevated position and the entire holder being concealed by the collar and the necktie.

4. A necktie holder comprising a bar, means on the ends of said bar to enable ready mounting of the holder on the collar and ready removal therefrom, and pin means projecting from the bar for engaging into the rear upper portion of the necktie, to hold the necktie in an elevated position on the collar.

5. A holder for holding a necktie in an elevated position on a turn-down collar, said holder comprising a curved bar to be placed forwardly of the collar band and in a direction extending longitudinally thereof, there being a rearwardly extending offset portion at each end of said bar and resilient looped clasping means depending from each

offset portion, for clasping on the collar band and to hold said bar offset forwardly from the band and press against the rear of the necktie, and pin means projecting forwardly from the bar for engaging into the rear of the necktie to positively hold it in the selected position on the collar, the holder being concealed by the collar and the necktie.

In testimony whereof I have signed my name to this specification.

ERNEST S. WOOLLEY.
